UNITED STATES PATENT OFFICE

LEO GREENBAUM, OF NEW YORK, N. Y., ASSIGNOR TO LION MATCH COMPANY, INC.,
OF NEW YORK, N. Y., A CORPORATION OF NEW YORK

ADVERTISING DEVICE

Application filed May 15, 1931. Serial No. 537,638.

This invention is an advertising device in the form of a splint packet. The packet embodies a plurality of splints integrally united to a base portion from which the 5 splints are individually removable. The comb is made from cardboard, veneer, paper, or other suitable material and each splint is headed, as by dipping, with an ignition composition, a cosmetic, a medicament or other 10 suitable composition depending upon the particular utilitarian purpose to which the packet is adapted.

It has heretofore been proposed to employ splint packets as an advertising medium and, 15 in fact, the majority of book matches made are dispensed in the interests of advertising places of business and articles of commerce.

Since the advent of the splint packet, the 20 general character of the packet, particularly with regard to book matches, has not appreciably varied. The packets have invariably been made with a cover enclosing one or more combs, each of which combs carries nine or ten splints. These splints are made 25 from cardboard or veneer, are about one and one-half inches in length and have a width of approximately one-eighth of an inch. For the last 25 years, book matches have been made in this way with the relatively 30 long attenuated splints. These narrow splints of the conventional form are not individually susceptible to any useful advertising purpose and consequently, the advertising matter carried by such packets has,

35 almost exclusively, been printed upon the inside or outside of the cover which affords ample space for such printing. The individual matches or cosmetic splints, per se, have heretofore served the one and only purpose 40 for which their head or tip adapted them—their advertising value has been little if any.

With the foregoing considerations in 45 mind, the object of the present invention is to make the device more valuable and serve a double or twofold purpose. That is to say, each splint of the comb of this invention has its normal utility as a match, cosmetic or medicament carrier, and it also has the further and additional characteristic that it

comprises, per se, an advertising device of compelling sales value for the places or products which it is utilized to advertise.

An important feature of the invention resides in the fact that the value of each individual splint, as an advertising medium, persists or continues subsequent to its removal from the comb.

The present invention is characterized by a packet construction wherein the comb is provided with splints, each of which has a width of at least one-seventh of its length and at least four times its thickness, each splint being provided with a head preferably of less width than the width of the splint, so that when the splints of a comb lie in the same plane, the heads will be spaced apart and free from contact with one another while the contiguous edges of the splints are for the greater portion of their length in substantially abutting relation. Through the provision of a comb of the character described, I am able to obtain results which have heretofore been impossible of accomplishment in combs of the prior art. With such a splint it is possible to pictorially represent thereon, in proper or natural proportions, articles of commerce, persons and places correlated to the subject matter to be advertised, in such a natural or lifelike manner that they arrest the attention of the buying public, foster good will and promote sales to an astonishing extent.

Features of the invention, other than those adverted to, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a perspective view showing an advertising device embodying the present invention.

Figure 2 is a front elevation of one of the combs removed from the packet shown in Figure 1.

Figure 3 is a section on the line 3—3 of Figure 2.

In the drawings, 1 designates a comb comprising a base portion 2 from one side of which projects a plurality of integral splints 3. Along the line where the splints are integrally united with the base, a line of scoring 4 may be provided, so that these splints may be made easily individually removable by tearing the splints from the base. The free end portion of each splint is provided with a neck 5 of reduced width which if desired may carry an integrally enlarged end portion 6. This end portion may, if desired, be of the same width as the neck, but if enlarged, as shown in Fig. 2, it is preferably of greater width than the neck, but of less width than the corresponding splint. In either event, each end portion 6 is adapted to carry a tip or head 7 of composition material, such as ignition material, cosmetic composition or a medicament which may be conveniently applied to the end portion 6 by dipping the combs into a bath of such composition and permitting the composition to harden. It will be noted that the size of the tip or head is preferably such that it is of less width than the width of the splint which carries it, so that when all the splints occupy the same plane, the tips or heads will be free from contact with one another.

By reference particularly to Figs. 2 and 3, it will be noted that the width α of each splint 3 is generally greater than one-seventh the length y of the splint. For example, if y equals approximately one and one-half inches, α should not be less than three-sixteenths of an inch and is preferably made even wider in accordance with this invention. The thickness z of the splint should, to give the best results, be approximately one-fourth the width α of the splint, although, in practice, the thickness z may be greater or less than the dimension given.

A splint constituted as described will embody marked rigidity. If tipped or headed with an ignition composition, it may be used as a match and struck upon an appropriate ignition surface without bending or breaking. Similarly, when used with a medicament or a cosmetic, the composition at the end of the tip may be applied to the person without the composition coming in contact with the hands through bending or breaking of the splint, while the line of scoring at the base of the splint permits of its ready removal from the comb.

The proportion of the length of the match to its width is such as to permit of printing or otherwise delineating upon the face of each individual splint, the picture of a human figure of life-like proportions. These proportions are such as to permit of printing on the face of each individual splint an individual picture correlated with any subject

matter which it is desired to advertise. In the showing of the drawings, a full length figure is printed upon the face of the splint between the line 4 and the head 7 may have a width bearing the proper relationship to the figure height. Thus, it will be noted from Fig. 2 that the splint provides ample space for printing thereon, an individual picture correlated with subject matter to be advertised. In the present instance, if it be desired to advertise a restaurant, the pictures on the individual splints may be those of waitresses holding trays. I wish it understood, however, that the invention is not limited to a splint with a picture of a human figure thereon. Any other individual picture correlated with the subject matter to be advertised may be delineated on each individual splint.

In the drawings, each splint is shown having substantially conventional thickness and length, but the width is approximately twice that of a conventional match splint, so that it can properly act as a carrier for both the head and the pictorial lifelike representation of the individual delineated thereon.

In practice, one or more combs of the character described and shown in Fig. 2 are adapted to be bound within a cover 8 after the manner of a conventional book match packet, a staple 9 being utilized to hold the cover in position and the combs in place within the cover. Two combs are shown in the packet of Fig. 1, but the invention is not to be understood as limited to this number.

It is of importance to note that when a splint is removed from the comb and held in the hand of a prospective user, it, per se, constitutes a complete and operative advertising device and this fact continues even after the splint is used and discarded. Lying in an ash tray or on a dressing table with, for example, the photograph of a restaurateur printed on its surface, the splint compels attention and continues as an advertising medium.

In the appended claims, I have referred to printing of pictures upon the individual splints. I wish it understood that any suitable picture may be printed on each splint and that the printing referred to is to be understood as covering surface printing, lithographing, embossing, photography and analogous known methods of delineating upon a surface a pictorial representation of some article, place or person.

The foregoing detailed description sets forth the invention in its preferred practical form, but the invention is to be understood as fully commensurate with the appended claims.

Having thus fully described the invention, what I claim as new and desire to secure by Letters Patent is:

1. As a new article of manufacture, an ad-

vertising device embodying a splint packet having a cover, a comb secured within said cover and comprising a base portion from one edge of which extends a plurality of integral, individually removable splints, each splint having a width of at least one-seventh of its length, a head of composition material on each splint, and, on the exposed face of each individual splint, a complete picture correlated with subject matter to be advertised, whereby each splint continues to have advertising value after removal from the comb.

2. As a new article of manufacture, an advertising device embodying a splint packet having a cover, a comb secured within said cover and comprising a base portion from one edge of which extends a plurality of integral, individually removable splints, each of which splints has a body portion provided near its free end with a reduced neck portion, said body portion having a width of at least one-seventh of the length of the splint, an enlarged end portion carried by the neck portion, said end portion having a width greater than the neck portion and less than the body portion, a head of composition material applied to said enlarged end portion of each splint, and, on the exposed face of each splint, a complete picture correlated with subject matter to be advertised, whereby each splint continues to have advertising value after removal from the comb.

3. As a new article of manufacture, an advertising device embodying a splint packet having a comb comprising a base portion from one edge of which extends a plurality of integral, individually removable splints, each splint having a width of at least one-seventh of its length, a head of composition material on each splint, and, on the exposed face of each individual splint, a complete picture correlated with subject matter to be advertised, whereby each splint continues to have advertising value after removal from the comb.

4. As a new article of manufacture, an advertising device embodying a splint packet having a comb comprising a base portion from one edge of which extends a plurality of integral, individually removable splints, each of which splints has a body portion provided near its end with a reduced neck portion, said body portion having a width of at least one-seventh of the length of the splint, an enlarged end portion carried by the neck portion, said end portion having a width greater than the neck portion and less than the body portion, a head of composition material applied to said enlarged end portion of each splint, and, on the exposed face of each splint, a complete picture correlated with subject matter to be advertised, whereby each splint continues to have advertising value after removal from the comb.

5. As a new article of manufacture, an advertising device embodying a splint packet

comb having a plurality of individually removable splints, each of which has a width of at least one-seventh of its length, a head of composition material on the free end of each of said splints, said head being of less width than the width of the splints, and, on the exposed face of each of said splints, a complete picture correlated with subject matter to be advertised, whereby each splint continues to have advertising value after removal from the comb.

6. As a new article of manufacture, an advertising device embodying a splint packet comb having a plurality of individually removable splints, each of which has a width of at least one-seventh of its length, a head of composition material on the free end of each of said splints, and, on the exposed face of each of said splints, a complete picture correlated with subject matter to be advertised, whereby each splint continues to have advertising value after removal from the comb.

7. As a new article of manufacture, an advertising device embodying a splint packet comb having a base portion from one edge of which extends a plurality of integral, individually removable splints, each of which has a width of at least one-seventh of its length, and, on the exposed face of each of said splints, a complete picture correlated with subject matter to be advertised, whereby each splint continues to have advertising value after removal from the comb.

8. As a new article of manufacture, an advertising device embodying a splint packet having a cover, a comb secured within said cover and comprising a base portion from one edge of which extends a plurality of integral, individually removable splints, a head of composition material on each splint, and, on the exposed face of each individual splint, a complete picture correlated with subject matter to be advertised, whereby each splint continues to have advertising value after removal from the comb.

In testimony whereof, I have signed the foregoing specification.

LEO GREENBAUM.
